UNITED STATES PATENT OFFICE

2,006,998

GUITAR PLAYING DEVICE

Vito L. Marzullo, Chicago, Ill.

Application July 19, 1934, Serial No. 735,942

5 Claims. (Cl. 84—320)

This invention relates to improvements in guitar playing devices, and more particularly to means for mechanically picking or plucking the strings by an arrangement of keys which are pressed down by the fingers to produce the same effect as would otherwise be produced with the fingers in direct contact with the strings.

The device is capable of being adapted to all stringed instruments which are played by vibrating the strings with the fingers or by a pick held in the fingers, as for example the banjo or mandolin, but for the purpose of the present disclosure is especially designed for the guitar and particularly when played after the manner of the Hawaiian or "steel" guitar, that is, with the instrument held horizontally on the lap of the player and fretted by sliding a steel bar along the strings to produce the metallic twang characteristic of Hawaiian music. Otherwise the strings are vibrated by picking or plucking them with the fingers, but usually with the aid of one or more picks which are fitted onto the thumb and one of the fingers of the playing hand, not only to produce more resonant and sustained notes or chords, but also to protect the fingers.

One of the objects of the invention is therefore to obviate the necessity of using such mechanical finger aids as just mentioned, or in the absence thereof, to necessitate the player maintaining a calloused condition of the fingers in order to withstand the harsh contact with the strings. Moreover, if the player is also accomplished on other instruments as well, a calloused condition of the fingers is frequently detrimental to the playing of other instruments, or if the player is a member of an orchestra and is required to play more than one instrument, it is quite impossible to change quickly from the guitar to another instrument or vice versa, because of the delay in removing or applying the mechanical finger aids.

A further and obvious object of the invention is to simplify the playing of stringed instruments by providing mechanical means for vibrating the strings through the medium of keys.

And finally, the object of the invention is to provide a self-contained attachment which can be applied to any guitar or like instrument without necessitating any alteration in the instrument or the provision of means to receive it.

A preferred embodiment of the invention is disclosed in the accompanying drawing, in which

Figure 1 is a perspective view of a guitar equipped with the playing device.

Figure 2 is a view in side elevation with two of the sections in vertical section as taken on line 2—2 of Figure 4.

Figure 3 is a view in vertical section taken on line 3—3 of Figure 2.

Figure 4 is a top plan view of the device with portions broken away to show two of the units in cross section as taken on line 4—4 of Figure 2.

Figure 5 is a plan view of the top cover plate 10 showing its sectional construction.

Figure 6 is a perspective view of one of the string vibrating elements.

Figure 7 and 8 are illustrative views showing the positions of the string vibrating members immediately before and after contact with the string.

The playing device is applied to the guitar as shown in Figure 1 at the point where the strings are normally vibrated manually, namely, just forwardly of the bridge and adjacent the opening in the body of the instrument. The frame of the device has the appearance of an elevated keyboard bridging the strings S, and is preferably constructed of a light material such as wood, or moulded of some equally light and durable material such as bakelite.

The frame preferably consists of a series of upright integral sections arranged in staggered relation, that is, alternately offset on opposite sides of a longitudinal central wall 2 and surmounted by a rectangular keyboard 3. These sections provide vertical housings for a group of key-operated string-vibrating units corresponding in number and spacing to the strings of the instrument to be played. Thus for a guitar with six strings S as shown, there is a corresponding vibrating unit and key for each string. At the base of the frame is a plurality of transversely spaced vertical slots 2a formed in the central wall and offset to one side of each of the sections 1. These slots straddle the strings when the device is applied to the instrument, thus locating each string adjacent one of the vibrating units.

Immediately beyond the playing device is a bridge 4 located in its usual position on the top wall 5 of the guitar body and having spaced notches 4a for the strings. The bridge serves its usual function of spacing the tensioned strings and is otherwise similar to the bridge with which the instrument is originally equipped, except that it is preferred to have the bridge connected directly to the frame of the playing device, as for instance by screws 4b as shown in Figure 2, 55

with the notches 4^a in alignment with the vertical slots 2^a in the frame.

Each unit 1 of the frame is shaped to house and support a string vibrator assembly, and for this purpose is shaped at its lower end to provide an enlarged chamber 1^a rectangular in section, and a vertical annular passage 1^b extending through the portion of the unit above the chamber and communicating therewith. The cover plate 3 (Figure 5) is rectangular in shape, but is preferably made in two sections fitting together along a staggered parting line 3^a conforming to the outline of the staggered units below, and provided with apertures 3^b for the keys as will later be described in greater detail.

Mounted in the annular passage 1^b of each unit is a key 6 having an enlarged circular head 6^a and a shank 6^b flattened on two sides and otherwise conforming to the shape of the openings 3^b in the keyboard 3 which holds keys against turning and likewise limits their endwise movement. The lower end of the shank is enlarged as shown at 6^c in Figure 6, and this enlargement provides a stop engaging the under side of the cover plate to determine the upward limit of the key movement. It is therefore to permit the assembly of the keys in the keyboard that the latter is made in two sections as heretofore described in connection with Figure 5. The shank of the keys is approximately one-half the length of the passage 1^b, thus leaving a space at their lower ends to accommodate light coil springs 7 which bear against the ends of the keys and act to return the same to their retracted positions when released.

Pivotedly connected with the slotted lower end of each key is a light metal bar 8 extending downwardly through the springs 7 into the lower chamber 1^a, the length of this bar being such that in the raised position of the key its lower end terminates just above and to one side of the string to be vibrated. The lower end of each bar is bent approximately at right angles and preferably slightly more than a right angle to provide a finger 8^a projecting toward the adjacent string S, these fingers being the actual string vibrating members.

As already noted, the strings are not in vertical alignment with the keys but are offset laterally therefrom passing through the slots 2^a at the left of each chamber as shown in Figure 2, and therefore the wall of each chamber 1^a adjacent the string is slotted vertically as at 9, thus permitting the finger 8^a to project exterior the chamber to contact with the string. Immediately above the finger 8^a of each bar is a fixed cross member 8^b forming a pair of short laterally projecting arms positioned at right angles to the finger 8^a. These arms function as cam members in conjunction with a pair of spring actuated cams 10, 10 pivotally mounted on the end wall faces of the chamber and on opposite sides of the slot 9. These cams are small metal blocks roughly of an elongated diamond shape, having centrally located pivot pins 10^a which are journaled in the end walls 65 of the chamber just above the level of the strings S. These cams extend in a general vertical direction, but are permitted to turn through a small angle limited by the width of the chamber, but normally to assume an inclined position with their lower ends toward the strings as shown in full lines in Figure 2. Light helical springs 11 are connected with the ends of the pivot pins exterior the chamber and these springs act to hold the cams in their normal positions. The cams 10, 10 are in vertical alignment with the cross arm 8^b on the vi-

brator arm 8, and the cam action between the two in the act of pressing down and releasing the key will now be described, bearing in mind that the action is that of plucking or vibrating the associated strings in quite the same manner as it would be done with the finger.

In the first place, it will be observed that the bar 8 is pivoted at its upper end to key 7, so that it can oscillate slightly in a plane transverse to the string, and thus when a key is pressed the cam arm 8^b on the bar 8 comes into contact with the cams 10, 10 which are inclined toward the string, with the result that the bar is shifted laterally as it descends, thus carrying the finger 8^a obliquely toward and into contact with the string, pressing it downwardly as shown in Figure 7. Now at this point the cross arm 8^b has reached the pivot points of the cams 10, and as it passes these points the cams swing in a counter-clockwise direction to the position shown in Figure 8, allowing the arm 8^b to pass, and then swinging back to their normal position as in Figure 7 then released.

With the sudden release of the cams 10, 10, the bar 8 is free to shift laterally with the tension exerted by the depressed string on the finger 8^a, causing the latter to slide out of contact with the string and setting up the vibration that produces the desired note. Thus having set the string in vibration, the key spring 7 is immediately released, and by the action of the retracting of the bar 8, is thrown upwardly. But since the finger 8^a is below the vibrating string, it is essential that it return to its normal position without touching the string and thus dampening its vibration. The cams 10, 10 now act to prevent this, for in the upward movement of the bar 8 the cam arm 8^b strikes the outer inclined faces of the cams so as to guide the bar laterally and away from the vibrating string as it travels upwardly, said cams in the meantime having been reset by the tension of their springs, although they are free to oscillate sufficiently to permit the cam arm 8^b to pass and allow the bar to return to its normal position in readiness for the next note.

Needless to say, the same string vibrating assembly is duplicated for each string so that all that is visible on the top of the casing is a keyboard consisting of six keys arranged in staggered formation across the width of the strings. Thus with the playing device properly applied, the player fingers or plays the instrument merely by pressing the keys with the fingers instead of plucking or picking them, this being accomplished by reproducing the same action mechanically through the cam controlled movement of the mechanical picks or fingers 8^a.

Presumably some practice would be required before the change from the conventional method of playing is mastered, but once this is done the performance is equally satisfactory if not more finished, inasmuch as the vibratory period of the strings is more uniform and hence the tones truer and more resonant.

Having set forth a preferred embodiment of my invention, I claim:

1. A playing attachment for stringed instruments comprising a series of string vibrating units, each comprising a key actuated contact member normally positioned above its corresponding string, and a cam pivotally mounted in the path of said member and adapted to guide the same obliquely across the string when said key is depressed, and to shift its position after said string has been set in vibration to guide said member out of contact with the vibrating

string during its return movement to normal position.

2. A playing attachment for stringed instruments comprising a series of string vibrating units, each comprising a key actuated contact member normally positioned above and offset to one side of a corresponding string, and a spring actuated cam pivotally mounted in the path of said member and adapted to guide the same obliquely across the string when said key is depressed, and to shift its position after said string has been set in vibration to guide said member out of contact with the vibrating string during its return movement to normal position.

15 3. A playing attachment for stringed instruments comprising a plurality of key actuated string vibrating units, each comprising an endwise depressible bar having a picker finger at its lower end and a cam pivotally mounted in the path of said bar and operative to guide the finger into contact with its corresponding string when the key is depressed, and to return the same in a path remote from the vibrating string when the key is released.

20 4. A playing attachment for stringed instruments comprising a frame adapted to be mounted on the instrument to embrace the strings and having slots through which the strings extend, and a series of vertical chambers adjacent the several strings, a plurality of key actuated string vibrating units mounted in said chambers, each comprising an endwise depressible bar depending from its associated key, a cam pivotally mounted

in each chamber and in the path of said bar, the same being provided with a coating cam engaging member and a string contacting finger, said cam being operative to guide the finger into string plucking contact with its corresponding string when the key is depressed, and to return the same in a path remote from the vibrating string when the key is released.

5 5. A playing attachment for stringed instruments comprising a frame adapted to be mounted 10 on the instrument to embrace the strings and having slots through which the strings extend, and a series of vertical chambers adjacent the several strings, a plurality of key actuated string vibrating units mounted in said chambers, each 15 comprising a depressible key depending into its chamber, a spring acting to return the key to its elevated position, a bar pivotally connected with said key and having a picker finger at its lower end, a cam pivotally mounted in said chamber 20 adjacent the path of said bar and provided with cam faces normally positioned obliquely of said chamber, said bar having a cam projection adapted to contact with said cam during the downward movement of said bar to effect the 25 plucking of the strings by said finger as it passes the cam, and a spring acting on said cam to return the same to its initial position, whereby contact between the cam and said cam projection during the return movement of the bar guides 30 its finger in a path remote from the vibrating string.

VITO L. MARZULLO.
